UNITED STATES PATENT OFFICE.

LEROY G. GATES, OF BAKERSFIELD, CALIFORNIA.

CENTRIFUGAL SEPARATOR.

Application filed July 16, 1923. Serial No. 651,757.

To all whom it may concern:

Be it known that I, LEROY G. GATES, a citizen of the United States, residing at Bakersfield, in the county of Kern and State 5 of California, have invented certain new and useful Improvements in Centrifugal Separators, of which the following is a specification.

My invention relates to centrifugal separators especially adapted for separating sand and other heavy particles from mud laden fluids, slimes, or the like.

The object of my invention is to provide a machine of the described type which is simple in construction and effective and efficient in operation. A machine embodying the principles of my invention is well adapted for removing the sand and heavy particles from the mud fluid used in well drilling, where the cleaned mud fluid is circulated through the well and used as a vehicle to carry off the cuttings of the drill bit. My invention is not restricted to such use, however, but may be employed to advantage for 25 other separation processes. It is to be understood, moreover, that the form and construction of the machine embodying my invention may be varied considerably from that herein described and illustrated, without departing from the spirit of the invention as expressed in the claims hereto appended.

With this in view a preferred embodiment of my invention will now be fully described 35 with reference to the accompanying drawings, wherein:—

Fig. 1 is a central vertical section of my centrifugal separator.

Figs. 2 and 3 are sectional plan views 40 taken on the lines 2—2 and 3—3 of Fig. 1, respectively.

In the drawings, the reference numeral 1 designates a central vertical hollow shaft, preferably formed in two parts joined together permanently by a suitable bushing 2. A diaphragm or partition 3 separates the interior of the upper portion from that of the lower. The hollow shaft 1 is suitably journaled for rotation in radial bearings 4 and 45 an end thrust bearing 5, which are mounted in a stationary frame, certain members of which are shown at 6. An enclosed shell 7, forming the separating chamber, is fixed upon and supported by the hollow shaft 1, and the whole is caused to revolve about the axis of said shaft by a bevel gear 8 which

meshes with and is driven by a pinion 9, the latter being fixed upon a shaft 10 to which power may be applied from any suitable source not shown in the drawings. 60

The hollow shaft 1 carries a hopper 11 at its upper end, into which the material to be separated may be introduced as by means of a pipe 12. Fixed in said hollow shaft below said hopper is a spiral baffle 13, which is steep at its upper end, and flattens out at its lower end into a plane lying along the axis of the shaft 1. This baffle 13 is for the purpose of imparting rotary motion to the fluid entering the hollow shaft 1 without interfering with its downward motion through said shaft. Discharge apertures 14 are provided in said shaft, through which the fluid passes out into the space between two conical members 15 and 16 respectively, both being fixed upon said shaft and, therefore, rotating with it. Radially disposed vanes or baffles 17 extend across said space between the conical members 15 and 16, thereby causing the fluid, when it is discharged from said space, to have a rotary motion of the same speed as that of the entire chamber. 70

The lower conical member 16 has its wall extended downwardly to the bottom of the shell 7, and said wall is provided with apertures 18 in its lower portion through which the cleaned or sand-free mud fluid may enter the interior of said member 16. Said fluid then passes into the lower section of the hollow shaft 1 through apertures 19, and thence 80 passes out, downwardly, through said shaft section. The lower section of said shaft 1 is preferably provided with a vertically movable interior sleeve 20, by which the height of the discharge apertures 19 may be 85 controlled. Suitable means, not shown, may be provided for operating said sleeve. A spiral baffle 21 is mounted within the lower section of the hollow shaft 1, said baffle having a steep lower portion and its upper portion flattened into a plane lying along the axis of the shaft, so that the rotary motion of the fluid within said shaft is gradually arrested, regaining some of the power consumed when the rotating motion of the fluid 100 was first imparted to it.

In Fig. 1 of the drawings, the feathered arrows indicate the path of travel of the sand or heavy particles carried by the fluid, and the plain arrows indicate the path of the clean mud. It should be noted that the fluid is projected into the separating cham- 110

ber at a point considerably distant from the axis of rotation, so that said fluid at once enters a zone of strong centrifugal force, and separation is therefore rapid and effective. It should also be noted that rotation is imparted to the fluid before it enters the separating chamber, so that the unfavorable effects of eddies and churning are minimized. When the shell 7 is in motion, the level of the fluid therewithin may be represented by the curved line $a-a$, this level being controlled, at the center, to a certain extent by the vertical position of the sleeve 20. The centrifugal force, acting on the fluid as it leaves the space between the conical members 15 and 16, causes the sand and heavier particles to travel toward the outside of the shell 7, leaving the sand-free mud to pass through the apertures 18 into the interior of the lower conical member 16, and thence out through the apertures 19 and the central hollow shaft 1.

The shell 7 carries, at its opposite sides, shafts 22, suitably journaled for rotation at 23, and each provided with a helical elevator 24. The shafts 22 are rotated, at a relatively slow speed, by suitable gearing 25 mounted upon the top of the shell 7, said gearing receiving its motion, as the shell 30 revolves, from a fixed pinion 26 carried by the frame 6. Thus as the shell 7 revolves rapidly about the axis of the shaft 1, the helical elevators 24 are also rotated, at a much slower speed, within said shell, and said elevators lift the sand, which has been packed more or less densely about them, to the level of the discharge apertures 27, through which it is ejected by centrifugal force. This gearing 25 may, if desired, be provided with a protecting cover plate shown at 28 in Fig. 1.

It should be understood that the form and arrangement of the sand elevators 24 and their drive mechanism is not limited to the showing herein made. For example, more than two such elevators may be employed, or some well known type of elevator other than the helical ribbon herein shown may be used, but as such variations would readily suggest themselves to those skilled in the art, no attempt has been made to illustrate them, the form herein shown and described being regarded as sufficiently expressive of the principles of the invention.

It is, however, of importance that the movement of the heavier portions of the material set up by the elevators or conveyors shall not be opposed by the action of centrifugal force, in order to prevent the packing of such material about said conveyors, thereby reducing their effectiveness. For this reason, I prefer, in the form of machine shown, to position the elevators with their shafts 22 parallel to the axis of rotation of the shell 7, so that the movement

of the heavier material is vertical, and therefore at right angles to the direction of centrifugal force.

I claim:

1. A centrifugal separator comprising a rotatable shell, a central hollow shaft through which the material to be separated is introduced into said shell; a spirally formed baffle within said shaft for imparting initial rotary motion to the material, 75 said baffle having a relatively steep initial portion, and a relatively flat final portion; and means for separately removing from said shell the component parts of said material according to their respective densities.

2. A centrifugal separator comprising a rotatable shell; a central hollow shaft through which the material to be separated is introduced into said shell; a spirally 85 formed baffle within said shaft for imparting initial rotary motion to the material, said baffle having a relatively steep initial portion and a final portion parallel to the axis of said shaft; and means for separately 90 removing from said shell the component parts of said material according to their respective densities.

3. A centrifugal separator comprising a rotatable shell adapted to receive the material to be separated; a central hollow shaft for removing a separated portion of said material; and a spiral baffle within said shaft for arresting the rotary motion of 95 said separated material.

4. A centrifugal separator comprising a rotatable shell adapted to receive the material to be separated; means for removing a separated portion of said material from the central region of said shell; and means 100 for arresting the rotary motion of said separated material during its removal from said shell.

5. A centrifugal separator comprising a rotatable shell adapted to receive the material to be separated; means for imparting rotary motion to the material prior to its introduction into said shell; means for removing a separated portion of the material from the central region of said shell; and means for arresting the rotary motion of 110 said separated material during its removal from the shell.

6. A centrifugal separator comprising a rotatable shell adapted to receive the material to be separated; a central hollow shaft about which said shell is mounted, said shaft having an aperture through which a separated portion of said material may be discharged, and a sleeve associated with said shaft and movable from the exterior of said shell for controlling said aperture and the discharge of the separated material there-through.

7. A centrifugal separator comprising a 130

rotatable shell adapted to receive the material to be separated; a central hollow shaft upon which said shell is carried, said shaft having an aperture through which a separated portion of said material may be discharged; and a sleeve movably associated within said shaft for controlling the aperture thereof.

8. A centrifugal separator comprising a rotatable shell adapted to receive the material to be separated; a central hollow shaft upon which said shell is carried, and through which a separated portion of said material may be discharged; and means within said shaft for arresting the rotary motion of said material during its discharge.

9. A centrifugal separator comprising a rotatable shell; a central hollow shaft upon which said shell is carried; means for introducing the material to be separated into said shell through a portion of said shaft; means within said shaft portion for initially imparting rotary motion to said material; means for removing a separated portion of the material from said shell through a second portion of said shaft; and means within said second shaft portion for arresting the rotary motion of said material during its discharge.

10. A centrifugal separator comprising a shell adapted for rotation about a vertical axis; a pair of spaced conical members positioned co-axially within said shell and adapted to rotate therewith; means for feeding the material to be separated into said shell through the space between said members; and means for discharging a separated portion of said material from the central region of said shell beneath the lower conical member.

11. A centrifugal separator comprising a rotatable shell adapted to receive the material to be separated; means for discharging the lighter portions of said material from the central region of said shell; and a conveyer for forcibly removing the heavier portions of said material from the peripheral region of said shell in a direction not opposed to the action of centrifugal force, said conveyer being remote from the axis of the shell and adapted to prevent the packing of said material against the peripheral shell wall.

12. A centrifugal separator comprising a

rotatable shell adapted to receive the material to be separated; means for discharging the lighter portions of said material from the central region of said shell; and a conveyer positioned in the peripheral region of said shell remote from the axis thereof, for agitating and forcibly removing the heavier portions of said material therefrom in a direction not opposed to the action of centrifugal force.

13. A centrifugal separator comprising a rotatable shell adapted to receive the material to be separated; means for discharging the lighter portions of said material from the central region of said shell; and a helical conveyer for removing the heavier portions of said material from the peripheral region of said shell, said conveyor having its axis parallel to and remote from the axis of said shell.

14. A centrifugal separator comprising a shell adapted to receive the material to be separated, said shell being rotatable about a vertical axis and provided with a discharge aperture in the upper region of its peripheral wall; and means for forcibly elevating the heavier portions of said material in the peripheral region of said shell, in a direction not opposed to the action of centrifugal force, to the level of said discharge aperture.

15. A centrifugal separator comprising a shell adapted to receive the material to be separated, said shell being rotatable about a vertical axis and provided with a discharge aperture in the upper region of its peripheral wall; and conveying means for vertically elevating the heavier portions of said material in the peripheral region of said shell to the level of said discharge aperture.

16. A centrifugal separator comprising a shell adapted to receive the material to be separated, said shell being rotatable about a vertical axis and provided with a discharge aperture in the upper region of its peripheral wall; and a helical conveyor rotatable about a vertical axis positioned in the peripheral region of said shell for elevating the heavier portions of said material to the level of said discharge aperture.

In testimony whereof I have signed my name to this specification.

LEROY G. GATES.
